HEATING UNIT CIRCUIT BREAKER

Filed Dec. 19, 1933

UNITED STATES PATENT OFFICE

2,072,822

HEATING UNIT CIRCUIT BREAKER

Robert J. Parsons, Schenectady, N. Y., assignor
to Consolidated Car Heating Company, Inc.,
Albany, N. Y., a corporation of New York

Application December 19, 1933, Serial No. 703,041

9 Claims. (Cl. 219—20)

This invention relates to electricity, particularly to electric heating, and more especially to the circuits and apparatus used therein.

Those acquainted with the art of electric heating, especially the heating of electrically propelled vehicles, are aware that the management is often in unskilled hands, and consequently the circuits and apparatus connected therewith must be such that it is easily manipulated, rugged in 5 construction, easily maintained, and so designed that positive assurance is secured that the electric current will not be allowed to flow through the heating units after the space in which they are placed reaches a certain temperature.

10 A principal object of the present invention is to provide a system of circuits for heating installations, and the necessary automatic circuit breakers in connection therewith such that safety in use, easy manipulation, and the greatest degree 15 of freedom from maintenance troubles will be secured.

Other objects and advantages will appear as the description of the particular physical embodiment selected to illustrate the invention progresses and 20 the novel features will be particularly pointed out in the appended claims.

In describing the invention in detail and the particular physical embodiment selected to illustrate the invention reference is had to the accompanying drawing wherein like characters of 25 reference designate like parts throughout the several views, and in which:

Figure 1 is a front elevational view of a circuit breaker embodying my invention; Fig. 2 is a side 30 elevational view of the device as shown by Fig. 1; Fig. 3 is a top plan view of the device as shown by Fig. 1; Fig. 4 is a schematic view illustrating the connections and arrangement of the device, as shown by Figs. 1 to 3 inclusive, in connection 35 with a heating device.

The circuit breaker as shown by Figs. 1 to 3 inclusive, comprises essentially a pivoted electrical conducting arm controllable both manually and electro-magnetically.

40 In Fig. 1 the electric conducting arm is designated 1. It is attached in any suitable or appropriate manner, as by riveting, to the two arm lever 2. The two arm lever 2 is pivoted in any suitable or appropriate manner, as by pivot pin 3, supported by the extended arms 4 and 5. The pivot pin 3 is so placed that the conducting arm 1 cooperates with a stationary contact 6 when in one position, but is separated therefrom when in another of its positions, as shown by dash lines 45 in Fig. 1.

The two arm lever 2 is provided with a latch engaging shoulder 7 and is adapted to cooperate with the shoulder 8 of a latch 9. When the shoulder 7 of the two arm lever 2 cooperates, as shown in Fig. 1, with the shoulder 8 of the latch 5 9, the conducting arm 1 is in cooperative relation with the conducting contact 6. The two arm lever 2 also cooperates with a stop 10 which limits its movement in one direction.

The latch 9 is pivoted in any suitable or appropriate manner, as by the pivot pin 11 supported by the outstanding bearings 12 and 13, so that it is free to oscillate. The latch 9 also carries a limiting shoulder 14 which is positioned and adapted to limit the movement of the two arm 10 lever 2 in a direction away from the stop 10 so that when the limiting shoulder 14 cooperates with the two arm lever 2 the conducting arm 1 is in the dash line position as shown in Fig. 1.

The stop 10, the extended arms 4 and 5 and the 15 extended arms 12 and 13 are attached to a coil housing 15, preferably integral. This coil housing 15 is made of metal preferably, a magnetic metal, which not only protects and encloses a wire coil 16, but is attached to one end of a magnetic core 17, as by screw 18, thus forming part of the magnetic circuit of the electro-magnet having the coil 16.

A flange 18' extends from the lower end of the housing 15 and supports headed pins 19. These 20 pins 19 in turn support the armature 20.

The energization of the coil 16 by electric current causes the armature 20 to rise, as viewed in Fig. 1, and in so doing to lift the latch rod 21. This latch rod 21 is guided in bores 22 and 23 in 25 the arms 5 and 10, and so positioned that when it rises it contacts with the latch 9 and raises the latch. When the latch 9 is raised the shoulder 8 is removed from cooperative relation with the shoulder 7 of the two arm lever 2, so that the two arm lever 2 is free to be moved outwardly to the dash line position as shown in Fig. 1, catching on the limiting shoulder of the latch 9 and thereby 30 breaking contact between the conducting arm 1 and the conducting contact 6. To insure the arm 40 2 catching on the limiting shoulder 14 the latch 9 is provided with a limiting tail piece 24 which contacts with the coil protector 15 to prevent the right hand end of the latch 9, as viewed in Fig. 1, from rising to such a height that the two arm 45 lever 2 may pass beyond the limiting shoulder 14 of the latch 9.

In order to insure the movement of the two arm lever 2 from the full line position to the dash line position as shown in Fig. 1, applicant pref- 50 55

erably provides a bias. This bias, in the preferred form, is an expansible member or compression spring 25, only one of which appears in the drawing, positioned between lever 2 and spring 5 abutments as 26, preferably formed integral with the protecting casing 15.

After lever 2 has moved into the dash line position, as shown in Fig. 1, it is returned to normal position in contact with contact member 6 by a 10 manual movement. In order to facilitate this movement applicant prefers to provide a manipulating button 27. This manipulating button is 15 preferably made of insulating material and is attached to one arm of the two arm lever 2 in any suitable or appropriate manner as by screw 28.

The device hereinbefore described furnishes a rugged, substantial, easily manipulated and easily maintained circuit controller especially suitable for use in connection with heating circuits which 20 are manipulated by comparatively unskilled persons.

In Figure 4 applicant has schematically shown a preferred arrangement of circuits and apparatus for energizing and controlling a heating 25 unit.

In Fig. 4 a source of operating and heating current is connected with the wire 29 in which is interposed the manually operable switch 30 of any desired form. When the switch 30 is closed, that 30 is, makes contact with the wire 31, current may flow to and through the non-inductive resistance 32, to the wire 33, relay coil 34, and wire 35 to the conducting arm 1 and from conducting arm 1 through the two arm lever 2 and wire 36 to the 35 other side of the source of potential.

Current flowing in the above traced path energizes the relay coil 34 and so causes the armature 37 to be raised so as to make contact with wire 38. As soon as this contact is made between 37 and 38, 40 current then flows from the positive terminal of the source through wire 29, switch 30, wires 31 and 38, armature 37 and wire 39 to the several heating coils 40 and then to the negative terminal of the source.

Thermostat 41 is positioned so as to be influenced by the heat generated by the heating coils 40. When the temperature has arrived at a certain high value, the thermostat 41 will close its contacts 42 and 43 so that a shunt path is provided from the junction of resistance 32 and wire 33 to the negative terminal of the source which so decreases the current flow in current 34 that the armature 37 is released, or drops to its lower position, as shown in Fig. 4, so cutting off the 55 supply of electrical energy to the heating coils 40. When these coils and the space heated thereby are sufficiently cool, the thermostat again opens its contacts 42 and 43, and, if switch 30 is closed, the coils are again supplied with energy.

It might very well be that thermostat 41 would fail to act properly so that a continuous supply of energy would be fed to the heating coils 40; or a short circuit of some one of the coils 40 might occur sending a greater amount of current 60 through the other coils; or the vent for the space being heated by the coils 40 might be accidentally closed; or a blower motor blowing air over the coils 40 might become defective and stopped. This would either finally burn up the coils or cause 65 a dangerous rise of temperature in the space within which the coils are situated. In order to provide for this, applicant provides a thermostat 41 which is illustrated as being of the ordinary bi-metallic rod type which bends in one direction 70 by decrease of temperature and in the other by 75

the increase of temperature. In Fig. 4 the thermostat 44 is shown in the open position. If the temperature caused by the coils 40 rises too high, that is, higher than would be necessary to cause thermostat 41 to close its contacts, and thermostat 41 fails to close its contacts, then thermostat 44 makes contact at its upper end, as shown in Fig. 4, with post 45. The current could then flow from armature 37 through wire 46, non-inductive resistance 47, wire 48, coil 16, wire 49, 10 post 45, thermostat 44, and wire 50 to the negative terminal of the source. Current flowing in the above traced path would energize coil 16 and cause armature 20 to be raised thereby raising latch rod 21 and lifting latch 9 so that lever 2, by 15 reason of springs, as 25, moves into a position corresponding with the dash line position of Fig. 1, that is, so that conducting arm 1 breaks contact with contact point 6. As soon as 1 and 6 separate, relay coil 34 becomes de-energized and armature 37 drops and cuts off the supply of energy to the heating coils 40, thereby insuring that they 20 will not become unduly heated or burn out.

Even if the temperature falls to a proper value 25 after thermostat 44 has broken the circuit at armature 37, the circuit will not be re-established at armature 37 until the button 27 has been manually manipulated to restore the conducting arm 1 to its cooperative connection with contact 6, so that if the circuit breaker is open due to a defect, it would not, of itself, again close the circuit so that current may be supplied to the heating coils, and at the same time the attention 30 of the operator will be arrested both by the visible movement of button 27 and by the "click" of 35 the resetting action of the switch, which thus yields an audible signal to the person operating the button 27. The operator will thus be advised that the defect exists and must take the necessary steps to rectify the same, as such repetitive 40 action will occur as frequently as the button 27 is pushed in, so long as the defective condition 45 obtains in the circuit.

Applicant's arrangement of heating and controlling circuits is simple, easy to maintain, and 45 susceptible of use by one not highly skilled, furthermore, is particularly safe in that the controlling and governing devices are simple and rugged and once automatically operated must be 50 returned to normal condition by a manual operation.

Although I have particularly described one particular physical embodiment of my invention and explained the principle and operation thereof, nevertheless, I desire to have it understood 55 that the form selected is merely illustrative but does not exhaust the possible physical embodiments of the idea of means underlying the invention.

What I claim as new and desire to secure by 60 Letters Patent of the United States, is:

1. In a heating arrangement, in combination: a heating coil; means for supplying electrical energy to said coil including a relay armature; means for controlling the armature of the relay 65 including an electro magnetic circuit breaker and a relay coil for said relay armature; a thermostat including contacts bridged when the thermostat is exposed to one temperature and un- 70 bridged when the thermostat is exposed to another low temperature, said contacts, when bridged, included in a shunt circuit around said relay coil whereby the relay coil becomes sufficiently de-energized to fail to control the armature whereby the heating coil circuit is open 75

another thermostat, said thermostat arranged in a circuit, including the electro-magnetic circuit breaker, in shunt to the heating coils, said last mentioned thermostat arranged to close said last mentioned circuit upon being exposed to above a given temperature and to open the circuit when exposed to below the said temperature and means for manually closing the relay coil circuit after being opened by the electro-magnetic circuit breaker, whereby when the electro-magnetic circuit breaker is energized the relay coil circuit is broken.

2. A heating arrangement including a heater circuit; electric heating means in said circuit; a control circuit for said heater circuit; an electro-magnetic relay included in, and operated by, said control circuit, and adapted to establish and break said heating circuit; exclusively automatic means for operating said control circuit, comprising a thermostat; a secondary control circuit for said heating circuit comprising an electro-magnetic circuit-breaker, and a second thermostat co-operating therewith exclusively for breaking said heater circuit; and an exclusively manually operable means for re-setting said circuit-breaker to re-establish said heater circuit.

3. A heating arrangement including a heater circuit; electric heating means in said circuit; a control circuit for said heater circuit; an electro-magnetic relay included in, and operated by, said control circuit, and adapted to establish and break said heating circuit; exclusively automatic means for operating said control circuit, comprising a thermostat; a secondary control circuit for said heating circuit comprising an electro-magnetic circuit-breaker, and a second thermostat co-operating therewith exclusively for breaking said heater circuit; and an exclusively manually operable means for re-setting said circuit-breaker to re-establish said heater circuit, said second-named thermostat being effective independently of said first named thermostat.

4. A heating arrangement including a heater circuit; electric heating means in said circuit; a control circuit for said heater circuit; an electric switch comprising an armature and a relay coil included in, and operated by, said control circuit, and adapted to establish and break said heating circuit; a thermostat responsive to a given degree of temperature, and serving as exclusively automatic means for operating said control circuit; a secondary control circuit for said heating circuit, comprising an electro-magnetic circuit-breaker, and a second thermostat effective independently of the other thermostat and co-operating with said circuit-breaker exclusively for breaking said heater circuit; and an exclusively manually operable means for operating said circuit-breaker to re-establish said heater-circuit.

5. A heating arrangement characterized by the elements combined and co-operating as set forth in claim 1, and further characterized by having said electro-magnetic circuit breaker and said second-named thermostat so included in circuit with said relay coil that during continued operation of said second-named thermostat, after any operation of the means for manually closing the relay circuit, said electro-magnetic circuit breaker will again break the relay coil circuit, and at the same time cause a visible movement of said manually operable means accompanied by an audible click or signal, both of which are adapted to arrest the attention of the operator, repeatedly.

75 6. A heating arrangement characterized by the

elements combined and co-operating as set forth in claim 3, and further characterized by having said electro-magnetic circuit breaker and said second-named thermostat so included in circuit with said relay coil that upon continued existence in said heater-circuit of an abnormally heated condition after operation of said manually operable means, said electro-magnetic circuit breaker will again break the heater circuit, and at the same time cause a visible movement of said manually operable means and an audible click or signal both adapted to arrest the attention of the operator.

7. An electric heating system characterized by an electric heater circuit including an electrically energizable heater and a circuit-closing switch therefor, a magnet controlling said switch, a circuit for said magnet shunting the heater, with a thermostat adjacent to the heater, and responsive to a predetermined degree of heat therein, which controls the said magnet, together with a second thermostat responsive independently of said first-named thermostat to an excessive temperature of the space to be heated and included in a control circuit with said magnet and with a control device comprising a pivoted electrically conductive circuit-breaker arm in series with said magnet, and also comprising means to actuate said arm, a controlling means for said arm, a second electro-magnetic means to operate said arm-controlling means to open the circuit of the first-named magnet and thereby de-energize said heater, and means capable of exclusively manual actuation to move said arm to a position in which the circuit of the first-named magnet will be closed, and in which said control circuit will again become effective in response to said condition of overheat.

8. An electric heating system characterized by an electric heater circuit including an electrical energizable heater and a circuit-closing switch therefor, a magnet controlling said switch, a circuit for said magnet shunting the heater, with a thermostat adjacent to the heater, and responsive to a predetermined degree of heat therein, which controls the said magnet, together with a second thermostat responsive independently of said first-named thermostat to an excessive temperature of the space to be heated and included in a control circuit with said magnet and with a control device comprising a pivoted electrically conductive circuit-breaker arm in series with said magnet, and also comprising means to bias said arm to circuit-breaking position, a bias-controverting means capable of exclusively manual actuation to move said arm to a contact-making position in which the circuit of the first-named magnet will be closed, and whereby the dual control of said first-named magnet by said control circuit and by said shunt will again become normally effective in response to said heat conditions; said control device having also a latch to hold said arm in said contact-making position, and another electro-magnetic means in series with said second-named thermostat and adapted to trip said latch when the second-named thermostat is closed.

9. An electric heating system characterized by an electric heater circuit and a circuit closing switch therefor, a magnet controlling said switch, a circuit for said magnet shunting the heater; a circuit shunting said magnet and including a thermostat responsive to changes of heat in the space to be heated and adapted to condition said magnet circuit normally to control the operation of said heater circuit and thereby maintain a pre-

determined degree of heat in said space; said system being further characterized by another relay circuit shunting said heater circuit, and including a relay coil and another thermostatic device responsive to excessive heat from said electric heater; a circuit-making-and-breaking device for said first-named magnet circuit and adapted to be operated by said relay shunt circuit, and means to bias said device to open the same, thereby to de-energize said first named

magnet and consequently to de-energize said heater; a bias-controverting means exclusively operable by direct manual pressure to its bias-controverting position, thereby to close the magnet circuit and cause said heater to be energized and means operable by said relay coil when energized by the closing of said second named thermostat, to permit said bias to become effective; whereby said heater will be de-energized.

ROBERT J. PARSONS. 10
